UNITED STATES PATENT OFFICE.

FREDERICK WILHELM ROETTGES, OF NEW YORK, N. Y., ASSIGNOR TO ROYAL ART GLASS CO., A CORPORATION OF NEW YORK.

DESIGN FOR SPINDLE FOR LAMPS, LIGHTING FIXTURES, OR SIMILAR ARTICLES.

Application filed April 10, 1924. Serial No. 9,224. Term of patent 3½ years.

To all whom it may concern:

Be it known that I, FREDERICK W. ROETTGES, a citizen of the German Republic, and a resident of the city of New York, county of Kings, and State of New York, have invented a new, original, and ornamental Design for Spindle for Lamps, Lighting Fixtures, or Similar Articles, of which the following is a specification, reference being had to the accompanying drawing, forming a part hereof.

The drawing shows an elevational view of the spindle for lamps, lighting fixtures or similar articles.

I claim:

The ornamental design for spindle for lamps, lighting fixtures, or similar articles as shown.

FREDERICK WILHELM ROETTGES.
